UNITED STATES PATENT OFFICE.

ARTHUR E. WHITE, OF CHICAGO, ILLINOIS.

SPRING COT OR LOUNGE.

No. 802,250.

Specification of Letters Patent.

Patented Oct. 17, 1905.

Application filed December 28, 1904. Serial No. 238,661.

To all whom it may concern:

Be it known that I, ARTHUR E. WHITE, a citizen of the United States, residing at Chicago, in the county of Cook and State of Illinois, 5 have invented certain new and useful Improvements in Spring Cots or Lounges, of which the following is a specification.

The invention relates to that type of spring cots or lounges in which the reposing part of 10 the cot or lounge has a rising-and-falling movement given thereto from springs at one end thereof.

The objects of the present invention are to construct a spring cot or lounge with companion side frames, each side frame having a bottom rail continuing at its forward end to form a coil, with a top rail rearwardly extending from the coil, the bottom rail, the coil, and the top rail being made of a single rod or bar; 20 to furnish a form of spring connecting the bottom rail and top rail and so arranged in relation to the rails at their front ends as to allow the top rail to rise and fall in a uniform and easy movement; to have the top rail de- 25 part from the curvature or circle of the spring-coil, so as to give an upward inclination for the side rail at an angle that when an occupant is on the reposing-section of the cot or lounge the resiliency of the spring-coil ex- 30 tends for the length of its entire circle without any strain on one part more than on another part, thus insuring an easy and perfect rising-and-falling movement, and to improve generally the arrangement of the several parts 35 entering into the construction of the cot or lounge as a whole.

The invention consists in the features of construction and combinations of parts hereinabove described and claimed.

40 In the drawings, Figure 1 is a perspective view showing the support formed of two companion side frames having a similar construction; Fig. 2, a similar view to Fig. 1, showing a canvas or covering stretched over the top rails of the side frames; and Fig. 3, a perspective view showing a mattress on the top rails of the side frames and a basket or receiver on the bottom rails of the side frame.

The support is formed of two companion 45 side frames A, each side frame having a bottom rail a , which at its forward end is curved around to furnish a spring-coil a' , extending rearwardly from which is a top rail a^2 , the rails and spring-coil being integral and formed 55 of a single rod or bar, and the top rails preferably are of greater length than the bottom

rails, so that when the cot or lounge has an occupant thereon the weight will be sustained by the spring-coils and will be supported on the base-rails in such manner as to give an 60 easy rising-and-falling movement for the top rails through the resiliency of the spring-coils, which resiliency extends over the entire circle of the coils by reason of the departure of the curve for the inner end of the top 65 rails from the true circle of the body of the spring-coils, which departure is one that will cause the up-and-down movement of the top rails to extend continuously around the circle of the coil instead of an increased tension at 70 one point of the spring-coil.

The side frames A at the rear ends of the bottom rails a are connected together by a cross-bar b , the ends of which are secured in legs or feet b , depending from a socket b' , entered onto the end of each side rail, and when in position locked and held by a set-screw b^2 or otherwise. Each leg or foot b has journaled in its end a caster ball or wheel b^3 , serving as a rolling support for the cot or lounge. 80 The bottom rails a at their front ends are connected together by a cross rod or bar C, the ends of which are entered into legs or feet c , depending from a socket c' , adjustable on the side rail, and when adjusted locked and held in 85 position by a set-screw c^2 or otherwise. Each leg or foot c has journaled in its lower end a caster ball or wheel c^3 , completing the rolling support for the cot or lounge as a whole. The rear ends of the top rails a^2 are connected to- 90 gether by a cross-bar D, the ends of which are entered in bosses d , each boss extending out from a socket ball or head d' , entered onto the end of the top rail and locked thereto by a set-screw d^2 or otherwise. A cross rod or bar E 95 is located at the forward end of the top rails a^2 , with the ends of the cross rod or bar E secured in bosses e , extending out from sockets e' , each socket secured to its top rail by a set-screw e^2 or otherwise, so that the cross rod or 100 bar E can be adjusted as required for the re- ception of the canvas or covering F or for the attachment of a mattress G of any usual construction. The canvas F has its side edges 105 f turned over the top rails a^2 and secured by stitching or otherwise, and has its forward end f' turned over the cross rod or bar E and secured by stitching or otherwise, and has its rear end f^2 turned over the cross rod or bar D and secured by stitching or otherwise. 110 The canvas is drawn taut by means of the cross rod or bar E, and when taut the rod or

bar is locked in place by the set-screws, so that the canvas or covering F will furnish a proper support for a mattress or for the occupant if a mattress is not desired. The mattress can be mounted on the canvas or covering F, as shown by the dotted lines in Fig. 2, or the mattress can be attached direct to the top rails and the cross-bars by securing the side edges g of the mattress in any suitable manner to the side rails and securing the front end g' in any suitable manner to the cross rod or bar E and securing the rear end g'' of the mattress to the cross-bar D and the rear ends of the top rails in any suitable manner. The construction shown in Fig. 3 has attached to the base of the support a basket H, having side walls h and end walls h' , the side walls being secured to the bottom rails a and the end walls being secured to the cross-bars B and C in any suitable manner.

The side frames are each formed of a bottom rail a , a spring-coil a' , and a top rail a'' , with the rails and spring-coil integral. The resistance to a weight supported on the top rails a'' extends through the entire circle of the spring-coils, and for this reason the occupant of the cot or lounge has a uniform and easy rising-and-falling movement without any sudden jar or concussion. The weight of the occupant counterbalances and serves as a counterpoise for the resiliency of the spring, and by the occupant adjusting himself or herself higher or lower on the mattress or canvas the weight of the occupant can be shifted, so as to give a perfect and reliable counterpoise against the resiliency of the spring-coils, thereby giving a uniform, easy, and perfect rising-and-falling movement in use. The weight of the occupant is carried by the spring-coils, starting at the initial turn of the coils at the forward ends of the bottom rails, and the weight of the occupant is supported on the base-rails, so as to hold the cot or lounge in position in use against movement from the rise and fall of the top rails.

The two side frames are duplicates of each other, so that no time or trouble is wasted in assembling the parts, as any two side frames can be used together with the assurance of being correct and of proper construction. The cross-bar C is slipped onto the bottom rails A and advanced to its forward position, and the cross-bar B is slipped onto the bottom rails at the rear ends thereof, and when in position the bars are secured to the bottom rails by the set-screws or other suitable means. The cross-bar E is slipped onto the top rails and advanced to its forward position and there secured by the set-screws or other suitable means, and the cross-bar D is entered onto the rear ends of the top rails and there secured by set-screws or other suitable means. It will thus be seen that the assembling of the parts is readily and quickly accomplished, and when assembled the support as a whole is

firm and unyielding except as to the free and easy rising-and-falling movement of the top rails when the cot or lounge is occupied.

The support as a whole is of simple construction, and at the same time, owing to the manner of forming the bottom rails, the spring-coil, and the top rails for the two companion side frames all from a single rod or bar for each side frame, the support is well adapted for the application of a canvas or covering or for a mattress, either of which can be readily applied to the top rails.

The cot or lounge when completed will be found very desirable, as in use the occupant will not be subjected to any jar or concussion arising from the effects of the spring-coil, and in addition the weight of the occupant can be so adjusted in relation to the spring-coils as to give a free, easy, and perfect rising-and-falling movement in use.

What I claim as new, and desire to secure by Letters Patent, is—

1. The combination of two companion side frames, each consisting of a bottom rail, a spring-coil and a top rail departing from the spring-coil at its front side with an upward incline toward its rear end, the two rails and the spring-coil being integral and formed from a single rod, a cross-rod for the rear ends of the bottom rails, a socket at each end of the cross-rod entered onto the bottom rail, locking means for the sockets to the bottom rails, a cross-rod for the front ends of the bottom rails, a socket at each end of the cross-rod entered onto the bottom rails, locking means for the sockets on the bottom rails, a cross-rod for the front ends of the top rails, a socket for each end of the cross-rod, locking means for the sockets to the top rails, a cross-rod for the rear end of the top rails, a socket at each end of the cross-rod, and locking means for the sockets to the top rails, substantially as described.

2. The combination of two companion side frames, each consisting of a bottom rail, a spring-coil and a top rail departing from the spring-coil at its front side with an upward incline toward its rear end, the two rails and the spring-coil being integral and formed from a single rod, a cross-rod for the rear ends of the bottom rails, a socket at each end of the cross-rod entered onto the bottom rail, locking means for the socket to the bottom rails, a cross-rod for the front ends of the bottom rails, a socket at each end of the cross-rod entered onto the bottom rails, locking means for the sockets on the bottom rails, a cross-rod for the front ends of the top rails, a socket for each end of the cross-rod, locking means for the sockets to the top rails, a cross-rod for the rear end of the top rails, a socket at each end of the cross-rod, locking means for the sockets to the top rails, a covering attached to the top rails and the front and rear cross-rod, substantially as described.

3. The combination of two companion side frames, each consisting of a bottom rail, a spring-coil and a top rail departing from the spring-coil at its front side with an upward incline toward its rear end, the two rails and the spring-coil being integral and formed from a single rod, a cross-rod for the rear ends of the bottom rails, a socket at each end of the cross-rod entered onto the bottom rail, locking means for the sockets to the bottom rails, a cross-rod for the front ends of the bottom rails, a socket at each end of the cross-rod entered onto the bottom rails, locking means for the sockets on the bottom rails, a cross-rod for the front ends of the top rails, a socket for each end of the cross-rod, locking means for the sockets to the top rails, a cross-rod for the rear end of the top rails, a socket at each end of the cross-rod, locking means for the sockets to the top rails, and a mattress attached to the top rails and to the front and rear cross-rods of the top rails, substantially as described.

4. The combination of two companion side frames, each consisting of a bottom rail, a spring-coil and a top rail departing from the spring-coil at its front side with an upward incline toward its rear end, the two rails and the spring-coil being integral and formed from a single rod, a cross-rod for the rear ends of the bottom rails, a socket at each end of the cross-rod entered onto the bottom rail, locking means for the sockets to the bottom rails, a cross-rod for the front ends of the bottom rails, a socket at each end of the cross-rod entered onto the bottom rails, locking means for the sockets on the bottom rails, a cross-rod for the front ends of the top rails, a socket for each end of the cross-rod, locking means for the sockets to the top rails, a cross-rod for the rear end of the top rails, a socket at each end of the cross-rod, locking means for the sockets to the top rails, and a mattress attached to the top rails and to the front and rear connecting-rods of the top rails, substantially as described.

for the front ends of the top rails, a socket for each end of the cross-rod, locking means for the sockets to the top rails, a cross-rod for the rear end of the top rails, a socket at each end of the cross-rod, locking means for the sockets to the top rails, a receptacle attached to the bottom rails and the front and rear connecting-rods, substantially as described. 45

5. The combination of two companion side frames, each consisting of a bottom rail, a spring-coil and a top rail departing from the spring-coil at its front side with an upward incline toward its rear end, the two rails and the spring-coil being integral and formed from a single rod, a cross-rod for the rear ends of the bottom rails, a socket at each end of the cross-rod entered onto the bottom rail, locking means for the sockets to the bottom rails, a cross-rod for the front ends of the bottom rails, a socket at each end of the cross-rod entered onto the bottom rails, locking means for the socket on the bottom rails, a cross-rod for the front ends of the top rails, a socket for each end of the cross-rod, locking means for the sockets to the top rails, a cross-rod for the rear end of the top rails, a socket at each end of the cross-rod, locking means for the sockets to the top rails, and a mattress attached to the top rails and to the front and rear connecting-rods of the top rails, substantially as described. 50

for the front ends of the top rails, a socket for each end of the cross-rod, locking means for the sockets to the top rails, a cross-rod for the rear end of the top rails, a socket at each end of the cross-rod, locking means for the sockets to the top rails, a covering attached to the top rails and the front and rear connecting-rods of the top rails, and a receptacle attached to the bottom rails and the front and rear connecting-rods of the bottom rails, substantially as described. 55
